BANDAGE

Filed June 26, 1923.

INVENTOR.
E. K. Stansell,

BY

Geo. P. Kimmel.

ATTORNEY.

Patented Aug. 3, 1926.

UNITED STATES PATENT OFFICE.

EMERY K. STANSELL, OF BUFFALO, NEW YORK.

BANDAGE.

Application filed June 26, 1923. Serial No. 647,837.

This invention relates to bandages, or that type what may be termed a legging, and has for its object to provide in a manner as hereinafter set forth, a bandage for spiral application to the leg and including a curved flexible body portion for exerting a firm, uniform pressure with no undue stretching when used, as well as to overcome the sealing up of the pores of the skin, cramping of the muscles or the nerves thereby assuring freedom of circulation and perspiration when the bandage is applied.

A further object of the invention is to provide in a manner as hereinafter set forth a bandage including a curved flexible body portion which when applied can be worn with comfort by those whose badly swollen limbs and varicose ulcers will no longer permit the use of either lace or elastic stockings.

20 A further object of the invention is to provide in a manner as hereinafter set forth, a bandage including a curved flexible body portion for spiral application to a limb, and having that part to be positioned from the 25 ankle to the calf of the leg, curved to provide a perfect fit with no reverse forming what may be termed a stocking.

A further object of the invention is to provide, in a manner as hereinafter set forth, 30 a bandage including a windable, flexible curved body portion for application spirally to the leg, and further with means for securing the body portion to the leg above the calf thereof and to prevent the body portion 35 from slipping below the calf.

Further objects of the invention are to provide, in a manner as hereinafter set forth, a bandage which is simple in its construction and arrangement, strong, durable, sanitary, 40 washable, thoroughly efficient in its use, conveniently applied, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood 45 that changes, variations and modifications 50 that changes, variations and modifications can be resorted to which fall within the scope of the claim hereunto appended.

In the drawings wherein like reference characters denote corresponding parts 55 throughout the several views:

Figure 1 is an elevation of a bandage in accordance with this invention, showing the application thereof to a leg.

Fig. 2 is an elevation illustrating the body portion of the bandage extended.

Fig. 3 is a perspective view of one of the holding elements.

Fig. 4 is a perspective view of the retaining element.

A bandage, in accordance with this invention, comprises a flexible body portion 5, of substantial width and of equal width throughout and further of substantial length. The body portion 5 is constructed of knitted fabric and preferably four inches wide, stretching approximately six inches to the yard, and narrowing to three and one-half inches in width. The body portion is constructed of fabric possessing a characteristic that it loses but little of its elasticity when worn, and is restored to perfect form by washing. The body portion 5 is set up to provide what may be termed a foot part 6, an ankle part 7, and a calf part 8. The calf part is upon a permanent substantial curve so disposed whereby when the body portion 5 is extended, the foot part 6, will be extended at an obtuse angle with respect to the calf part 8. The substantially curved calf part, is set up by providing the body portion 5 with four darts or gores and each of these latter is indicated at 9. Each of the cut out portions of the body 5 which form a dart may vary in width at the entrance from one and one-fourth to two and one-half inches. The cutout portions are triangular-shaped and these two angles meet about three-eighths of an inch from the upper side edge of the bandage. The edges of the cutout portions are drawn together and overlapping said edges is a tape 10 which extends over the lower edge of the body portion 5. The tape 10 is secured to the body portion 5 by the stitching 11 and owing to the manner in which the tape 10 is set up, it is positioned against each face of the body portion 5. The tape 10 takes the pull of the bandage and owing to the setting up of the body portion 5 with the cutout portions to form darts or gores and when the edges of each cutout portion are drawn together, the part 7 extends upon a substantial curve. The ends of each of the tapes 10, extend to within an eighth of an inch of the upper side edge of the body 5.

To accomplish a perfect 110

fit, of the bandage with respect to the leg, the distance between the darts or gores may vary from seven to twelve inches.

The upper end of the body portion 5, is 5 cut diagonally from each side edge to a point at the center, as indicated at 12, 13, and the corners and then turned in until they are brought together as indicated at 14. This arrangement forms what may be 10 termed a nose at the upper end of the body portion 5, and which is cut off to provide a flat edge about an inch wide, as indicated at 15. The inturned portions at the upper end of the body portion 5 are indicated at 16, 15 17. Arranged at the upper end of the body portion 5, as well as being secured therewith, is a tape preferably about eight inches long and one inch wide and which is indicated at 18. The tape 18 is extended between 20 the inturned portions 16 and 17 and projects from the upper end of the body portion 5 as well as projecting downwardly from the inturned portions 16, 17. The body portion 5, inturned portions 16 and 17, 25 and the tape 18, are secured together by the stitching 19. The tape 18, has each of its ends, pointed as at 20. When the tape 18 is set up, that part thereof which projects upwardly from the upper end of the body portion 5 is about three inches in length and that part of the tape 18 which depends from the inturned portions 16, 17, is also about 30 three inches in length.

Associated with the tape 18, is a retaining 35 element which consists of an elastic strap 21, provided at each end with a buckle 22. The pointed ends 20 of the tape 18, permit of the convenient insertion of the tape in the buckles 22. The strap 21 is of sufficient 40 length to correspond with the measure of the leg, extends around the leg, and has its buckles 22 connected with the tape 18, whereby when the body portion 5 of the bandage is applied to the leg 23, the bandage 45 is secured to the leg 23, above the calf, as clearly shown in Fig. 1.

To prevent the bandage from slipping below the calf of the leg, a pair of holding 50 elements are employed, and each of said holding elements consists of a body portion formed of a pair of tapes 24, 25, adjustably connected together, by the buckle 26. The tape 24 has secured to its upper end, an attaching element 27, for connection with the 55 step 21, as shown in Fig. 1. The tape 25, has one side thereof, provided with a pair of spaced attaching members 28, 29, one arranged above the other, and which are adapted to engage under two coils of the bandage 60 midway between the ankle and calf of the leg, and which when the holding element is in position, will prevent the slipping of the bandage below the calf of the leg. The

holding elements are arranged one on each side of the leg. The attaching members 28, 29, extend in an opposite direction with respect to the attaching member or element 27. The attaching members 28, 29, are so constructed, as not to cause any inconvenience to the wearer of the bandage.

The retaining element, in connection with the tape 18, overcomes the employment of rings or pins for the purpose of securing the bandage in position, and when the holding elements are connected with the retaining elements, the body portion of the bandage, when applied, is prevented from slipping, and in view of setting up the substantially curved part 7, the body portion 5 when applied to the leg, will cause a snug but comfortable fit of the bandage to the leg, and as the bandage when applied, does not seal up the pores of the skin, nor cramp the muscles, nor irritate the nerves, it is obvious that a bandage is set up which assures freedom of circulation and perspiration when applied, and although the preferred embodiment of the invention is as illustrated and described, yet it is to be understood that changes in the details of construction can be had which will fall within the light of the invention as claimed.

What I claim is:—

A bandage comprising a flexible body portion including a calf part, an ankle part 95 and a foot part, said ankle part extending downwardly and angularly disposed with respect to said calf part, said foot part disposed at an obtuse angle with respect to said calf part, said ankle part disposed permanently upon a substantial curve, said ankle part formed with spaced slits one at the point of joinder with the calf part and the other at the point of joinder with the foot part, means engaging with the ankle part for securing the edges of the slits together to maintain the ankle part of permanent curvature, a tape secured to the free end of the calf part and extending lengthwise of the body portion and having free 100 end terminal portions, one arranged parallel to the calf part and the other projecting therefrom, an elastic retaining element provided with a buckle at each end for detachably connecting it with the ends of said 105 tape to secure the body portion in position on the leg, and holding elements adjustably connected with said retaining element and provided on the inner face thereof with attaching members engaging the lower edge of 110 certain convolutions of said body portion when the latter is applied to the leg.

In testimony whereof, I affix my signature hereto.

EMERY K. STANSELL,
